DANIEL H. MELOCHE, OF BRONXVILLE, NEW YORK, ASSIGNOR TO AMERICAN RADIATOR COMPANY, OF NEW YORK, N. Y., A CORPORATION OF NEW JERSEY

METHOD AND MEANS FOR CASTING

Application filed September 25, 1926. Serial No. 127,642.

My invention relates broadly and generally to new and useful improvements in methods and means for the casting of metal objects, and particularly to casting of pistons and similar elements for use in internal combustion engines.

In the production of cast metal pistons for internal combustion engines, it is generally recognized to be highly desirable to produce a casting which will be of light weight, accurately cylindrical in external contour, having a relatively thin metal line of uniform thickness, and which will require a minimum amount of machining to render the casting available for installation. It is also desirable that such a casting be as free as possible of internal strains so that the same will not crack when being machined, or subjected to heat effects in service.

So far as I am aware, all prior available methods employing sand molds for casting metal pistons have required the use of cope and drag mold sections containing matching sand prints to form a mold, and the locating of a suitable core or cores in the mold, the cores being either part of the sand mold in the cope or drag, or separate from the cope and drag molds and supported in the mold by suitable means. While such methods have been used commercially, the use thereof has been attended with objectionable results, arising mainly from core shifts, swells in the casting, and occluded gases and internal strains in the casting, all of which resulted in non-uniformity in metal line, contour and weight, and in imperfect castings unfit for machining, or which cracked, due to internal stresses, resulting in a large loss. Furthermore, the prior methods have necessitated that the casting be made heavier and of a much thicker metal line than required in the finished or machined piston, so as to assure enough metal in the casting so that when finished it would meet the requirements of the specifications for the finished piston, so far as dimensions were concerned.

By the known methods it has been practically impossible to cast large numbers of pistons which will be of uniform weight,

uniform metal line, and true to dimensions prescribed by specification.

One of the important objects of my invention is to provide a method capable of producing castings which will be of uniform weight, of uniform thickness of metal wall, both individually and in quantities, and truly cylindrical in contour, so as to reduce to a minimum the machining operations necessary to finish the casting for use.

A further object is to dispense with certain foundry operations hitherto necessary to render the castings ready for machining, such, for example, as snagging sprues and grinding off fins, ridges or other excrescencies on the casting which were unavoidable in the old method of molding with cope and drag, and resulted from the difficulty of making all cope and drag molds match accurately.

A further object is to produce castings of the character mentioned, which will be free of objectionable internal strains which result in cracking during setting of the casting, during annealing, when machined, and when in service in an internal combustion engine.

A further object is to produce castings uniformly free of occluded gases, and therefore non-porous so as to reduce loss incidental to the occluded gases or porosity, and which can usually only be discovered after the casting has been partly or wholly machined, or when it is subjected to the stresses attending use.

A further object is to provide an apparatus which will successfully attain the objects heretofore set forth.

The invention consists in the novel method and apparatus for carrying the same into effect, to be more fully described hereinafter, and the novelty of which will be particularly pointed out and distinctly claimed.

In the accompanying drawings I have illustrated a preferred embodiment of an apparatus constituting my invention, and which constitutes one means for carrying my improved method into effect.

Figure 1 is a perspective view of a flask employed in the practice of my invention;

Fig. 2 is a perspective of a pattern element employed in carrying out the invention;

Fig. 3 is a top plan view of a core support and positioning member;

Fig. 4 is a perspective view of a preferred form of core;

Fig. 5 is a perspective view of a holding member for holding the cores in position in the core-supporting element shown in Fig. 3;

Fig. 6 is a longitudinal sectional view showing the elements illustrated in Figs. 1, 10 3, 4 and 5 assembled for the pouring of a mold, and

Figs. 7, 8 and 9 are detail sectional views showing the steps of performing the method previous to the assembly of elements shown 15 in Fig. 6.

Before proceeding with a detailed description of my invention, I would state that I have shown the same as embodied in an apparatus capable of providing for multiple casting, so as to permit the economical and 20 rapid production of a number of castings simultaneously. However, the invention is not to be limited to multiple casting, as it contemplates embodiment in either single or 25 multiple casting. In carrying out my invention in its preferred form, I employ a flask or mold 1, which is preferably rectangular in construction and open at its top and bottom. This mold box is preferably of a 30 depth sufficient to hold sufficient sand to form a sand mold for molding an entire piston casting. The top and bottom edge faces of the mold box are preferably made to lie in exact parallel planes in order to effect the 35 result to be hereinafter described. Opposite walls of the flask are provided with extensions or lugs 2, provided, respectively, with guide apertures 3, there being preferably a pair of such guide apertures in each lug, said 40 apertures being adapted to receive guide means preferably in the form of pins carried by a pattern-carrying element, and also by a core-supporting element to be hereinafter described.

45 4 designates a pattern element, preferably consisting of a flat plate or board, carrying on one side thereof patterns 5 of such shape or contour as to form in a green sand mold prints or cavities corresponding to the external configuration it is desired to impart to the casting. In the present embodiment each of these patterns is a true cylinder arranged with its longitudinal axis at right angles to the plane of the face of the pattern board, and symmetrically spaced thereon. The pattern board is provided with guide means preferably in the form of spaced pins 6 adapted to cooperate with the openings 3 in the lugs 2 to accurately position the patterns 50 within the flask 1 when the pattern element is applied to the open end of the flask (see Fig. 7). It will be understood that in the preferred form the apertures 3 in the lugs 2 on the flask and the pins 6 on the pattern board are so located that the pattern board is

reversible end for end with respect to the flask, so that the patterns will occupy a determined and accurate position in the flask. In forming the sand mold or print in the flask, the flask 1 is arranged on a suitable 70 support with the lugs 2 uppermost, and the pattern board 4 is then applied to the upper open end of the flask, being guided and held in position by engagement of the pins 6 thereon with the guide openings on the flask 75 (see Fig. 7). It will be understood that the under face of the pattern board is made preferably flat, and at right angles to the longitudinal axis of the patterns, so that when the pattern board is applied in position the patterns will project into the mold-containing 80 portion of the flask. It will be noted that these patterns are of such length that they terminate short of the bottom of the flask when in the position just described, so as to provide a casting space to form a piston. 85

The pattern board having been located on the flask as just described, the flask 1 is rolled over by any suitable agency, so that the pattern board 4 is located on the bottom of the flask with the patterns projecting upwardly in the latter (see Fig. 8). Mold-forming sand 7 is then placed in the flask and is rammed or packed therein about the patterns, and then any suitable means is employed to level the sand in the flask. The sand may be rammed, or packed by hand, or by any well known jolt, or squeeze mechanism. After striking of the mold a suitable bottom board 8 is applied thereto, the bottom board and the pattern board being held to the flask by any suitable means (not shown). The mold is then rolled over to bring the pattern board uppermost, as shown in Fig. 9, and the pattern is then drawn by any suitable means to separate it from the mold in the flask. As the result the flask contains a sand mold containing one or more cylindrical cavities or prints 9 which establish the external contour of the casting to be made. It will also be noted that each of these prints forms the external contour of a complete cylindrical piston casting, and that the print is located with its longitudinal axis at right angles to the plane of the upper edge of the flask and the face of the body of sand in the flask. Each of the prints in the mold is then ready to receive a core adapted to cooperate with the print 9 to form a casting, and in its preferred embodiment may form additional parts, for example, the gudgeon pin bosses for receiving the pin for connecting the finished piston to a piston rod. In its preferred embodiment the core consists of a baked or dried sand body formed according to any suitable formula of sand or other material, and binder adapted for the purpose. The core is preferably hollow, including a body portion 10 of such diameter and length that when inserted in a print, above de- 100 105 110 115 120 125 130

scribed, will provide an annular space to receive the metal to form the skirt of a piston casting and an end space communicating with said annular space to form a piston head integral with the skirt (see Fig. 6). The body portion of the core is preferably cylindrical, and at the juncture of the side face and end face may be provided an annular recess 11 adapted to form an internal fillet 11^a at the juncture of the head and skirt of the piston casting (see Fig. 6). At a point intermediate its ends the body portion may be provided with diametrically opposite recesses 12, which when the core is in position in the print communicate with the annular space in the print and receive the metal to provide the casting with internal bosses 12^a to receive a gudgeon pin for connecting the finished piston to a piston rod. At its upper end the core is formed with suitable means for closing the annular casting space 9 between the core and the print, and is also formed with means whereby the core may be supported by an end at a point external of the print and the sand mold in the flask. The said means for closing the annular space preferably consists of a circumferential shoulder or flange 13 having a preferably horizontal under face 14 extending laterally from the core and of such width radially that when the core is in position in the mold print said face extends beyond the edge of the print and cooperates with the mold to thereby close the annular space between the core and the print, and define the bottom edge of the skirt of the piston casting. By the shoulder 13 the casting space 9 is separated or insulated from the core-supporting means to be hereinafter described, and chilling of the casting which might result in objectionable internal strains, from contact with said means, is obviated. The core may be formed adjacent the face 14 with an annular recess 14^a to provide for an internal reenforce for the skirt of the piston casting. The said supporting means carried by or forming part of the core, comprises a head 15, also integral with the core, being formed of the same composition material, and in its preferred form is a laterally projecting member 16, preferably circular and located above projecting beyond the mold or print-closing shoulder 13. The center of the supporting head 15 is coincident with the longitudinal axis of the core, and the projecting part thereof is made equidistant from said center at all points to facilitate adjustment, as will be hereinafter described. The periphery of the member 16 is beveled downward and inward, as at 16^a. The core is preferably made hollow, and in its preferred embodiment is formed with an axial cavity 18 which opens at its top through the upper end of the core and terminates at its lower end, preferably at a point below the boss-forming re-

cesses 12 heretofore described. I provide for gating the mold, preferably by forming one or more pouring ports 19 communicating with the said pouring cavity and opening through the wall of the core into the said recesses, so that when the metal is poured into the cavity it flows through said ports into the recesses and into the space in the print around the core. 70

I provide means for supporting the core by its end portion or head, heretofore described, which projects above or beyond the mold or flask, and for accurately centering and holding the core in the print so that a uniform metal line for the skirt of the piston casting 75 is assured. This means preferably consists of a rigid member in the form of a plate 20 adapted to lie over and cover the top of the mold, and having guide and positioning pins 21 accurately positioned thereon to correspond to the position of the pins 6 on the pattern board, and the guide openings 3 in the flask. This plate carries means for supporting one or more of said cores so as to center the latter accurately in the print, and 80 for this purpose said plate is provided with one or more apertures 22 shaped to conform to or match the periphery of the supporting head on the core, said apertures being preferably circular and of such diameter that the 85 supporting flange 16 on the core will closely but removably fit the same. Each of the apertures is so located in the plate that when the latter is in position on the flask the center of each aperture will be coincident with the 90 longitudinal axis of the core in the aperture and the longitudinal axis of the print. The wall of each aperture is provided with an inwardly extending annular flange 23 having a horizontal supporting shoulder or face 24 95 upon which the supporting shoulder 17 on the core rests, and said flange is provided with a circular face 25, preferably inclined inwardly and downwardly to engage the correspondingly formed face 13^a on the 100 print-closing shoulder of the core. The wall of the aperture above the shoulder is beveled inwards at 24^a. It will thus be seen that when the plate is applied to the mold with its apertures over the print in the mold, a core may 105 be inserted through each said aperture to locate the body of the core in the print, and that when the core is so located the print-closing face 14 will project laterally over the edge of the mold in the flask; the inclined 110 face 13^a will contact the inner annular face 25 in the aperture, and the face 17 of the shoulder 16 will rest upon the shoulder 24 in the wall of the aperture. The face 16^a on the core 115 will seat against the beveled face 24^a in the wall of the aperture. By accurately forming the inner wall of the plate aperture, the shoulder 24 and the cooperating face 17 on the core, and also the inclined faces on the core and aperture, the core when inserted in 120 125 130

position to be supported by the plate will be accurately centered within the print and thereby assure a uniform metal line for the skirt and head. The cooperating inclined faces on the aperture and core head cause the core to be automatically centered in the aperture and print.

In the preferred form means is provided for holding the cores in the position just described to assure that they will not be dislodged, due to pressures generated in the mold when the latter is poured. For this purpose the upper end or head of the core is preferably made of such vertical thickness as to provide a horizontal face 28 in a plane at right angles to the longitudinal axis of the core and located above the upper face of the core-supporting plate 20, and the cores are held down by suitable means, as a weighted member, preferably in the form of a plate 29 adapted to rest upon the horizontal faces 28 when the cores are in place in the plate 20. This plate 29 is provided with pouring openings 30 which are located over the pouring cavities 18 in the cores. It will thus be seen that the cores are held from lateral movement in the prints due to pressures generated in the print, and that the plate 29 prevents longitudinal displacement of the cores from the prints. It will also be seen that the part 13 on the core which overhangs and closes the upper end of the print separates the mold cavity and therefore the molten metal therein, from access to and contact with any part which might act as a chill for the lower edge portion of the skirt of the piston casting. When the core is in position it merely contacts or rests lightly upon the edge of the mold and does not crush or break down the mold. This is accomplished by making the shoulder 13 of a proper thickness to effect the result stated. It will also be seen that the cores are supported by means which is external to the mold in the flask, so that deformation of the mold print due to any cause, cannot disturb the accurate position of the core in the print.

In carrying out the method, the supporting means consisting of the apertured plate 20 is adjusted over the open end of the mold and is accurately positioned thereon relative to the print by means of the cooperating guides consisting of the pins 21 and apertures 3. The cores are then dropped into place and are automatically centered and held in proper position relative to the print or cavity, due to the formation of the cooperating faces on the cores and said supporting plate. By making the apertures in the plate 20 and the supporting part of the cores circular, the cores may be applied without regard to any particular circumferential relation to the print, as they will be accurately centered no matter what angular position they bear while being inserted. The holding member

or weight 29 is then located over and upon the upper ends of the cores, so that the latter are rigidly held on the supporting plate, whereupon the metal is poured through the apertures 30 in the holding plate into the cavities in the cores to form the casting (see right-hand mold in Fig. 6). By the use of the member 29 and the manner of supporting the core by the plate 20, the core is held against movement in both directions longitudinally of the print. The casting A is substantially cylindrical, including the head B and cylindrical skirt C open at the end opposite to the head, and having the internal bosses 12^a heretofore mentioned. The sprue in the central pouring cavity of the core is indicated at D, Fig. 6, and is connected to the bosses by the metal in the pouring ports or gates 19.

In order to assure the greatest accuracy and permit replacement in case of wear, each of the apertures in the supporting plate may be lined with rings or liners 31 having the configuration above described for said apertures, this provision permitting ready replacement in case said liners become worn or defaced so as not to accurately center a core; but it will be understood that the supporting faces may be made either integral with the plate 20 or by means of such liners just described. The openings 3 may also be lined, if desired, with replaceable bushings 3^a.

By the above method and apparatus I am able to cast a metallic piston with practically any desired uniform thickness of metal line, but the invention is particularly useful in casting pistons to a specified weight with a comparatively thin metal line, inasmuch as the accurate positioning and holding of the cores enables me to obtain a thin metal line which will be uniform at all points and not greatly in excess of that of the finished product, so that a small amount of machining is necessary. It will also be seen that the metal line being uniform, the piston may be machined, as, for example, cutting the grooves for piston rings to the proper depth without danger of cracking or cutting through thin parts, which were liable to occur incident to the old methods.

It will also be seen that by casting the complete piston in the drag section of a mold, the casting will be truly cylindrical, requiring little machining, and be free from ridges which result from parting lines in sand molds of the cope and drag type, or ridges due to non-matching of molds of the cope and drag type, which it is difficult to avoid.

The method and apparatus provides not only for casting of pistons which will be cylindrical, of uniform metal line, light in weight, and free from internal stresses, but also provides, in the case of multiple casting, for the production of large quantities of such castings with facility and with comparatively slight loss, thereby not only improving the

quality of the casting but reducing the cost due to saving of metal and due to low losses from imperfect castings.

The invention has a further important advantage in that I am able to cast a piston of cast-iron, which will be sufficiently light in weight to compare favorably with pistons hitherto made of aluminum or alloys for the sake of lightness, this being due to the fact that by accurately positioning and holding the cores against lateral and longitudinal movement, it is possible to provide a casting with a uniformly thin metal line, for example, $\frac{1}{16}$ of an inch, both in the skirt and head, which was not possible in the old methods where it was required to considerably overweight the casting in order to assure sufficient metal line to machine it to specification. By providing a thin uniform metal line for the casting, it is possible to machine the same to a thickness of $\frac{1}{16}$ of an inch in the finished piston, the machining loss being reduced from at least 33 per cent. to an average loss of about one per cent.

What I claim and desire to secure by Letters Patent of the United States is:—

1. A molding apparatus of the character described comprising a flask body containing a sand mold having a print to form the external contour of a complete substantially cylindrical piston, a sand core in said print and coaxial therewith, said core having at one end a sand part cooperating with the sand mold to close the opening into the print, and also having a circumferential laterally projecting supporting part at said end, said supporting part being vertically offset from said closing part, and means supported by said body and positioned external to the mold for engaging said supporting part to hold the core against lateral and longitudinal movement in the print.

2. A molding apparatus of the character described comprising a flask body containing a sand mold having a print to form the external contour of a complete substantially cylindrical piston, a supporting plate member overlying the mold and external thereto, said supporting member being supported by said body and having an aperture therein over the print, coating means between said body and said supporting member for maintaining said aperture in a determined relation to the print, and a core in said print, said core and member having cooperating means whereby the core is supported in said aperture and maintained against lateral movement in the print.

3. A molding apparatus of the character described comprising a flask body containing a sand mold having a print to form the external contour of a complete substantially cylindrical piston, a supporting plate member overlying the mold and being supported by the flask body and having a shouldered

aperture therein, means between the flask body and the supporting member for maintaining the aperture in the latter in a determined relation to the print, and a core in said print and coaxial therewith and having a part engaging said shouldered aperture to support the weight of said core from said body to prevent injury to said sand mold and whereby the core is held against movement in the print.

4. A molding apparatus of the character described comprising a flask body containing a sand mold having a print to form the external contour of a complete substantially cylindrical piston, a supporting plate member overlying the mold and having a shouldered aperture for guiding a core into and centering the axis of the core coincident with the axis of the print, a core in said print and having a part external to the print and located in said shouldered aperture to hold the core coaxial with the print, and means for engaging said core part to hold the same against longitudinal movement in the print, said last-named means including a weighted member engaging the projecting end of the core.

5. A molding apparatus of the character described comprising a flask body containing a sand mold having a print to form the external contour of a complete substantially cylindrical piston, supporting means removably mounted on said body and overlying said mold and having a shouldered aperture therein to receive and guide a core into said print, a core coaxial with said print and having an end portion extending externally of the print and having at its end external to the print a sand part engaging said shouldered aperture whereby the core is held against lateral movement in the print and removably supported in the aperture, said core having a longitudinal pouring cavity gated through the side wall of the core into the print, and means overlying said supporting member and engaging the external end of the core to hold the latter against longitudinal movement in the print, said last-named means having a pouring aperture communicating with the cavity in the core.

6. A molding apparatus of the character described comprising a flask body containing a sand mold having a print to form the external contour of a complete substantially cylindrical piston, a supporting plate member removably mounted on said body and overlying the mold and external thereto and having an aperture therein over the print, coating guide means on said body and said supporting member for positioning and maintaining said aperture in a determined relation to the print, a core in said print and extending through the aperture in said member, and coating faces on the member and core for centering the core in the print.

7. A method of casting pistons, which comprises forming in a flask a sand mold having a cylindrical print for the external form of a complete cylindrical piston, positioning a core-supporting member on said flask, suspending a core from said member coaxial with said print, holding said core to prevent displacement thereof, and then pouring said mold. 70
8. A method of casting pistons, which comprises forming in a flask a sand mold having a cylindrical print for the external form of a complete cylindrical piston, positioning on said flask a core-supporting member having an aperture therethrough coaxial with said print, suspending a core through said aperture into said print, holding said core to prevent displacement thereof, and then pouring said mold. 75
9. A method of casting pistons, which comprises forming in a flask a sand mold having a cylindrical print for the external form of a complete cylindrical piston, fixing on said flask against horizontal movement a core-supporting member having an aperture therethrough coaxial with said print, suspending a core from said member through said aperture into said print, weighting said core to prevent displacement thereof, and then pouring the mold. 80
10. A molding apparatus for casting pistons, comprising a flask body having a substantially vertical surrounding side wall, guide means positioned oppositely and projecting from the external top portion of said side wall, said flask body containing molding sand having a cylindrical mold print formed therein, a plate member supported by and on said side wall and having a circular aperture therethrough of a diameter greater than the diameter of said print, said plate member being recessed about said aperture to provide an upward facing annular shoulder, means on said plate member cooperable with said guide means to position said plate member on said body with said aperture concentrically over said print, a sand core member in said aperture and removably supported by said plate member, said core member having a circumferential flange of a diameter substantially equal to the diameter of said aperture whereby said flange closes the top end of the annular metal receiving space and having a flange above and extending laterally from said first-named flange, said second-named flange cooperating with said upward facing shoulder to support said core member, and weight means supported by said core member and acting by force of gravity to hold said second-named flange against said shoulder. 85
